UNITED STATES PATENT OFFICE.

WILLIAM S. MOSES, OF TRACY, MINNESOTA.

ROTARY ENGINE.

No. 901,813.

Specification of Letters Patent.

Patented Oct. 20, 1908.

Application filed January 28, 1908. Serial No. 412,972.

To all whom it may concern:

Be it known that I, WILLIAM S. MOSES, a citizen of the United States, residing at Tracy, in the county of Lyon and State of Minnesota, have invented certain new and useful Improvements in Rotary Engines; and I do declare the following to be a full, clear, and exact description of the invention, such as will enable others skilled in the art 10 to which it appertains to make and use the same.

This invention relates to improvements in my rotary engine, described in Patent No. 814,389, issued March 6, 1906; and has for 15 its object to provide an engine of this kind which will run with a minimum of friction and a maximum of economy, and which may be cheaply manufactured and easily operated.

Another object is to provide in an engine 20 of this kind a simple and easily operated steam feed and exhaust mechanism whereby the engine may be reversed and whereby the cut off is so controlled that advantage is 25 taken of the expansion of the steam, and whereby the steam may be compounded.

Another object is to provide a roller abutment in sections provided with means to hold the abutment against the walls of the 30 housing steam channels, whereby the steam is constrained from passing the abutment.

Another object is to provide such an arrangement of parts, that an engine of this kind may be manufactured adapted for 35 speed, power and simplicity of operation, as may be desired.

In the annexed drawing, forming a part 40 of this specification,—Figure 1 is an end view of my engine; Fig. 2 is a plan view; Fig. 3 is a longitudinal sectional view; Fig. 4 is a section on the line 4—4 of Fig. 3. Fig. 5 is a view similar to Fig. 4, taken on the line 5—5 of Fig. 2, and showing a modified form of the eccentric piston. Fig. 6 is 45 a sectional view of the abutment; Fig. 7 is a detail view of the rotatable cut-off valve; Fig. 8 is a detail view of the feed and exhaust valve; and Fig. 9 is a detail view of the cutoff sprocket wheel.

As illustrated my engine comprises a base 1, a cylindrical casing 2 supported thereon, a housing 3, abutments 4 in said casing, eccentric pistons 5 in said casing, and a steam chest 6. I provide a feed pipe 9 to conduct 55 the steam through the steam chest 6 to the

abutment chamber 7. When great diversity of power and efficiency are desired, the steam chest 6 is provided with the rotatable cut-off valve 8, to be described hereinafter, and as shown in Fig. 4.

When speed or simplicity of construction and operation is desired, the steam chest 6 is left without the valve 8. In the cylindrical casing 2 are one or more eccentric pistons 5. These may be of any number desired, and for each eccentric there is provided feed and exhaust ports, as will be described, and an abutment 4. The eccentric pistons 5 are provided with spaced flanges 11, which are rotatively mounted on a power 60 shaft 12 extending through the ends of the casing 2 and provided with a rotatable means, not shown, for transmitting power. The peripheries of the flanges 11 closely fit the cylindrical casing 2; the flanges, the casing and the shaft being concentric. The flanges are spaced to snugly receive therebetween the abutment 4, the weight of the abutment and the steam pressure thereon causing the abutment to lie against the surface of the eccentric and to move up and down in the abutment chamber as the eccentric pistons rotate.

By reference to Figs. 4 or 5 it will be noticed that the abutment 4 lies against 85 the eccentric piston and the point most removed from its shaft is distant from the abutment, thereby forming two inclosures 12 and 13 bounded by the housing 3, the abutment, the piston and the cylindrical casing 90 2. Communicating with these inclosures are inlet ports 14 and 15, either of which may be opened as by the rotary inlet and exhaust valves 16 and 17 to pass live steam from the chamber 7 into either of the inclosures 12 95 or 13. As shown in Fig. 4, the inlet port 14 is open and the inlet port 15 is closed. When this is the case the exhaust port 18 is closed and the exhaust port 19 is open, as shown in Fig. 5.

The valves 16 and 17 are provided with segmental inlet openings 20, (Fig. 4), and segmental exhaust openings 21, (Fig. 5), which are cut at an angle to each other and situated on the valves 16 and 17, as clearly 105 shown in Fig. 8, so that when a valve closes its inlet port its exhaust port will be open and vice versa.

When the valves are in the position shown in Fig. 4, the inclosure 12 communicates with 110

the feed pipe 9, and the inclosure 13 communicates with the exhaust. It will thus be evident that the pressure will be greater in the inclosure 12 than in the inclosure 13, and the piston 5 will be driven in the direction of the arrow of Fig. 4.

The valves 16 and 17 are provided with handles 22, which may be used for stopping, starting and reversing the engine. The engine may be reversed by closing inlet port 14 and opening the inlet port 15, and may be stopped by closing both ports.

The engine as thus far described does not provide for the expansion of steam in the inclosures 12 or 13. To accomplish this, I employ in the steam chest 6 the rotatable cut-off valve 8, (Figs. 4 and 8). The valve 8 is provided with a shaft 24, passing longitudinally therethrough and rigidly held coaxial therewith by the supporting pipes 25, which form a steam-tight joint with both the shaft and the valve.

The outside of the valve 8 and the inside of the steam chest is of conical shape, the valve being held in the steam chest by the spring 26 pressing against the shaft 24, whereby wear is compensated and a steam-tight joint between the valve and steam chest is maintained. The opposite end of the shaft 24 is provided with a sprocket wheel 27 or the like, loosely mounted thereon and connected by the chain or band 28 to the wheel 29 on the shaft 12.

Beyond the wheel 27 on the shaft 24 is the lateral projection 30 adapted to contact one of the pins 31 or 32 in the wheel 27, whereby the cut-off valve 8 is constrained to rotate in step with the eccentric pistons.

The cut-off valve 8 is provided with openings 33 adapted for a portion of the rotation of the same to register with the passage 34 by which the steam chest 6 communicates with the abutment chamber 7. The cut-off valve 8 is also provided with openings 35 so disposed that one or the other of them registers and establishes communication with the feed pipe 9 when the openings 33 register with the openings 34. The openings 33, the projection 30, and the pins 31 and 32 are so positioned relative to the pistons 5 that the passage 34 is opened for only a part of the revolution of the piston 5, the passage 34 being closed during the latter part of the revolution of the piston, whereby the steam is allowed to expand, thus effecting economy of steam. The pins 31 and 32 are so spaced apart that contact of the projection 30 with one pin places the valve 8 in position for proper cut-off when the engine is run in one direction, and contact with the other pin places said valve in position for proper cut-off when the engine is running in the opposite direction. The wheel 27 is loosely mounted on the shaft 24 so that when the engine is reversed the changing of the pro-

jection 30 from one pin 31 or 32 to the other is automatic as will be readily understood.

If it is desired to run the engine without expansion, the valve 8 may be turned by hand until both of the passages 33 are open 70 with the passage 34, and then the pins 31 and 32 removed. It will be evident that the action then is the same as if the valve was lacking.

If desired the eccentric piston 5 may be 75 entirely round for speed, or it may be in the form shown in Fig. 5, in which the transverse connection thereof is so shaped that a supplementary and auxiliary valve or cut-off is thereby provided for closing the open 80 exhaust port 19 or 18 until the open inlet port 14 or 15 is closed by said valve that live steam may not be exhausted as otherwise would be; and also for restraining the feed supplied through the regular cut-off valve 8 85 and thereby varying the quantity of steam used. This is shown in Fig. 5, that is the cut-off 8 is just moving off the port 34 and as the eccentric is moving in the direction indicated by the arrow in Fig. 4, steam is 90 evidently restrained by the auxiliary valve, from entering the inclosure 12, until the said valve has passed the inlet port 14 which restraining lessens, so much the regular feed provided by the valve 8 and thereby provides 95 for greater expansion and economy of steam and provides an engine with varying degrees of power.

For power, the shape shown in Fig. 4 is 100 desirable, as it provides that the inclosures 12 and 13 shall be of large steam capacity. This form may be made, as shown, supplementing the eccentric 5 with a segmental crest 36 to complete the piston, as shown.

In order to insure good contact at the ends 105 of the abutment 4 and to compensate for wear, if desirable, I may construct the abutment of two sections, a body section provided with a reduced end 37 adapted to be received by the end section 38, the outside 110 chamber of the body and end sections being the same. Against the circular end plate of each section I provide pushers 39 provided with shafts 40, rigidly and coaxially connected thereto and end to end, as shown. 115 Around said shafts is the coil spring 41, which pushes the sections outwardly against the end walls of the abutment chamber and against the flanges 11. To prevent steam escaping between the sections, I provide a 120 bushing ring 42, adapted to fill the space necessarily left between the sections after the parts are worn. These bushing rings may be replaced by thicker ones from time to time, as the abutment and chamber wear. 125 Instead of or in addition to the spring 41 and pushers I may use steam pressure to hold the abutment ends. I accomplish this by putting a small amount of water in the abutment, and when the live steam is turned 130

into the engine the water in the abutment is changed into steam, which tends to force apart the sections of the abutment. Instead of this means the natural expansion of heated air in the abutment may be taken advantage of, or the combination of the air and the spring may be used.

In Fig. 1 the various attachments of the sprocket wheel 27 are shown as arranged for regular feeding steam, with the eccentric shown in Fig. 4 and when the eccentric and cutoff valve are in the position shown in said figure. But when the cutoff valve 8 is provided for the eccentric shown in Fig. 5 the lug pins 31 and 32 are placed as shown in Fig. 9, for short steam feed and long expansion. It will be noted that there are two openings 31' and 32' for the lug pins; opening 31' for pin 31 and opening 32' for pin 32. When the regular feed is required the pins are placed in these openings.

It is thought that the operation and advantages of my invention will be understood without further described minute details. I do not limit myself to them as the details and arrangement of parts may be greatly varied without departing from the spirit and scope of the invention.

I claim as my invention:—

30 1. In combination, a cylindrical casing, an eccentric rotatively mounted therein, an abutment mounted to bear against said eccentric, and inlet and exhaust ports for said casing on opposite sides of said abutment, the length of said abutment being yieldably adjustable.

2. In combination, a cylindrical casing, an eccentric rotatably mounted therein, an abutment chamber, a cylindrical abutment in said chamber and bearing against said eccentric and dividing the casing into two inclosures, means to yieldably extend the length of said abutment, exhaust and inlet ports to said inclosures communicating with said chamber, a feed pipe, and a rotatable cutoff valve between said feed pipe and said chamber and connection between said valve and said eccentric, whereby said valve is constrained to rotate in step with said eccentric.

50 3. In combination, a casing, an eccentric having end flanges and rotatably mounted in said casing, an abutment chamber, an abutment therein and bearing against the ends thereof, against said end flanges and said eccentrics, whereby said casing is divided into two inclosures, exhaust and inlet ports for said inclosures, said abutment being divided into a body and an end section, said sections being adapted to contact the ends of said chamber to contact said end flanges, and means to yieldably force said sections apart.

4. In a rotary engine, a cylindrical casing, an eccentric rotatably mounted therein, an abutment chamber communicating with said

cylindrical casing, an abutment movable in said chamber and bearing against said eccentric to divide the cylindrical casing into two inclosures, inlet and exhaust ports communicating with said inclosures, rotatable valves for said ports, means adapted to rotate said valves, the valves of each of said inclosures being constrained to move together, whereby when one port is closed the other will be open, a tapering steam chest 70 communicating with said chamber, a feed pipe communicating with said steam chest, a cylindrical tapering rotary cut-off valve mounted in said steam chest, means to yieldably press said cut-off valve longitudinally 80 in one direction, openings in said rotary valve adapted to register with said feed pipe and the openings to said chamber through a portion of the revolution of said cut-off valve, and means adapted to rotate said cut-off valve in step with said eccentric, the openings of said cut-off valve being so positioned that steam pressure is admitted into said chamber throughout only a portion of the rotation of said eccentric. 90

5. In combination, a cylindrical casing, a piston rotatable therein, means to bear against said piston to divide it into two inclosures, inlet and exhaust ports communicating with said inclosures, a feed pipe, a tapering cylindrical steam chest communicating with said feed pipe and said inlet ports, a tapering cylindrical cut-off valve rotatably mounted in said steam chest, means to yieldably hold said cut-off valve against 100 movement in one direction, openings in said valve adapted to register with said feed pipe and said inlet ports, and means adapted to rotate said valve.

6. In a rotary engine, a rotary cut-off 105 valve, openings in said valve adapted to establish communication at the same time with the feed pipe and the cylinder of said engine, a shaft projecting from the end of said cut-off valve, a wheel loosely mounted on 110 said shaft, spaced stops on said wheel, a projection on said shaft lying between said stops, and means to rotate said wheel.

7. In combination, a cylindrical casing, a cylindrical eccentric rotatably mounted 115 therein, an abutment chamber, a cylindrical abutment in said chamber and bearing against said eccentric and dividing the casing into two inclosures, means to yieldably extend the length of said abutment, exhaust and inlet ports to said inclosures communicating with said chamber, supplementary means for controlling the flow of live steam to said inclosures by closing and opening said exhaust and feed ports in course, a 120 steam chest or feed pipe communicating with said chamber.

8. In combination, a cylindrical casing, a cylindrical eccentric piston mounted therein, an abutment chamber, a cylindrical abut- 130

ment in said chamber bearing against said eccentric and thereby dividing the casing into two inclosures, means to yieldably extend the length of said abutment, exhaust 5 and inlet ports leading to said inclosures, the inlet ports communicating with said chambers, a supplemental and auxiliary cut-off or valve, controlling, regulating and restraining the steam feed, through the said

inlet ports to said inclosures, substantially 10 as set forth.

In testimony whereof I have hereunto set my hand in presence of two subscribing witnesses.

WILLIAM S. MOSES.
